UNITED STATES PATENT OFFICE

107,092

DESIGN FOR A COMBINED BEVERAGE COOLING AND DISPENSING CABINET

Harry W. Ribble, Niles Center, Ill., assignor, by
mesne assignments, to Rapids Equipment Co.
Inc., Cedar Rapids, Iowa, a corporation of Iowa

Application July 10, 1937, Serial No. 70,359

Term of patent 14 years

To all whom it may concern:

Be it known that I, Harry W. Ribble, a citizen of the United States, residing at Niles Center, in the county of Cook and State of Illinois, have invented a new, original, and ornamental Design for a Combined Beverage Cooling and Dispensing Cabinet, of which the following is a specification, reference being had to the accompanying drawing, forming part thereof.

The figure is a perspective view of a combined beverage cooling and dispensing cabinet, show-

ing my new design, the left-hand end of the cabinet as viewed in the drawing being identical with the right-hand end shown, and the rear wall of the cabinet constituting simply a plane substantially vertical surface.

I claim:

The ornamental design for a combined beverage cooling and dispensing cabinet, as shown and described.

HARRY W. RIBBLE.
